(57) **CLAIM**

The ornamental design for a bottle assembly, as shown and described.

DESCRIPTION

FIG. 1 is a top perspective view showing my new design for a bottle assembly;

FIG. 2 is a front elevational view thereof—the rear, left, and right side views being identical thereto;

FIG. 3 is a top plan view thereof;

FIG. 4 is a bottom plan view thereof;

FIG. 5 is a top perspective view of a first embodiment of a bottle component of my new design for a bottle assembly, shown with an interior rim of the bottle unclaimed;

FIG. 6 is a front elevational view thereof—the rear, left, and right side views being identical thereto;

FIG. 7 is a top plan view thereof;

FIG. 8 is a bottom plan view thereof;

FIG. 9 is a top perspective view of a first embodiment of a stopper component of my new design for a bottle assembly, shown with the plug portion unclaimed;

FIG. 10 is a front elevation view thereof—the rear, left, and right side views being identical thereto;

FIG. 11 is a top plan view thereof;

FIG. 12 is a bottom plan view thereof;

FIG. 13 is a top perspective view of a second embodiment of a bottle component of my new design for a bottle assembly;

FIG. 14 is a front elevational view thereof—the rear, left, and right side views being identical thereto;

FIG. 15 is a top plan view thereof;

FIG. 16 is a bottom plan view thereof;

FIG. 17 is a top perspective view of a second embodiment of a stopper component of my new design for a bottle assembly, shown with the undercut and an interior rim of the plug portion unclaimed;

FIG. 18 is a front elevation view thereof—the rear, left, and right side views being identical thereto;

(Continued)

FIG. 19 is a top plan view thereof;
 FIG. 20 is a bottom plan view thereof;
 FIG. 21 is a bottom perspective view of a third embodiment of a stopper component of my new design for a bottle assembly, including the undercut and the interior of the stopper;
 FIG. 22 is a cross-sectional view thereof, taken from line 22-22 in FIG. 23; and,
 FIG. 23 is a bottom plan view thereof.
 The broken lines in the drawings depict portions of the bottle assembly that form no part of the claim.

1 Claim, 15 Drawing Sheets
